UNITED STATES PATENT OFFICE.

FRANK E. BOOTHROYD, OF BEVERLY, MASSACHUSETTS, ASSIGNOR TO UNITED SHOE MACHINERY CORPORATION, OF PATERSON, NEW JERSEY, A CORPORATION OF NEW JERSEY.

ELECTRICALLY-HEATED BURNISHING MACHINE.

1,410,053.

Specification of Letters Patent. Patented Mar. 21, 1922.

Application filed May 2, 1921. Serial No. 465,955.

To all whom it may concern:

Be it known that I, FRANK E. BOOTHROYD, a citizen of the United States, residing at Beverly, in the county of Essex and State of Massachusetts, have invented certain Improvements in Electrically-Heated Burnishing Machines, of which the following description, in connection with the accompanying drawings, is a specification, like referring characters on the drawing indicating like parts in the several figures.

This invention refers to electrically operated machines and is disclosed in connection with an electrically heated edge setting machine for burnishing the sole edges of boots and shoes. In machines having moving tools which it is desired to heat, the use of electricity for heating purposes has been found to present certain disadvantages owing to the difficulty of conveying the heat to the moving tool in case the heating unit is located upon the frame of the machine, and to the difficulty of conveying current to the unit in case it is located on the moving tool carrier in close proximity to the tool, since the consequent rapid movement of the unit has a tendency to cause deterioration and destruction in the leads which carry the current from the frame to the unit, whether these leads be continuous in form or whether they comprise moving contacts. I have found that electricity can be conducted successfully to a moving part by means of spiral springs with their axes substantially straight and preferably in a state of compression. These springs are made stiff enough so that their own weight or inertia has no appreciable effect upon their behavior, and the only movement which they evidence is due to the movement of the part to which they are connected. Accordingly an important feature of the invention consists in a lead comprising a spiral spring extending between the fixed frame of a machine and the moving tool carrier to which it is desired to convey electrical energy. This spring is preferably mounted in two sockets and held there simply by a certain compression sufficient to hold it firmly in place.

This and other features of the invention, comprising certain combinations and arrangements of parts will be understood from the following description of a preferred embodiment thereof selected for purposes of

illustration and shown in the accompanying drawings in which,

Fig. 1 is a side elevation, partly in section, of the machine.

Fig. 2 is a diagrammatic sketch of the oscillating mechanism; and

Fig. 3 is a plan view of the connecting leads.

The machine shown is the ordinary Ross-Moyer edge setter substantially such as is disclosed, for example, in United States Letters Patent No. 368,853, granted Aug. 23, 1887, on application of S. Ross. It comprises a rotary shaft 10 carrying a wrist pin 12 which causes a pitman 14 to oscillate horizontally. The pitman is pivoted at 16 to a vertical arm 18 carrying the edge setting tool 20 at its lower end. The arm 18 carries an arc-shaped member 22 having its center substantially at the working face of the tool 20 and this arc-shaped member 22 engages a flat ledge 24 mounted fixedly upon the frame of the machine, being held in contact therewith by a suitable spring. The rolling of the arc 22 upon the surface 24 causes the tool 20 to move substantially horizontally instead of in the arc of a circle. All of the foregoing structure is shown in the patent above referred to and need not be further described.

The arm 18 at its lower end is provided with a holder 26 in which is mounted a spindle carrying two tools 20 at its lower end. These tools can be interchanged by means of the handle 28, as is well understood. One tool is used on the shank and the other upon the forepart of the shoe. An electric heating unit is mounted in a casing 30 placed in any convenient location adjacent to the tools upon the holder 26. This unit is supplied by leads 32 with current passing through a suitable rheostat 34, and it is to the transference of the current from the fixed frame of the machine to the moving casing 30 that the principal features of this invention are directed. The leads 32 pass to terminal blocks 36 mounted upon the oscillating arm 18. Opposite these blocks on the fixed frame of the machine are a second pair of terminal blocks 38 to 105 which the leads coming from the rheostat 34 are attached. Compressed between corresponding members of these pairs of terminal blocks are two spiral springs 40. The terminal blocks are mounted in sockets in 110

two insulation blocks 42 and 44 and the ends of the springs are also mounted in these sockets resting against the terminal blocks as shown in Fig. 3. As the tool is vibrated, 5 the block 44, which is mounted upon the arm 18, is vibrated with it and the corresponding ends of the springs move in the same way. The ends of the springs which are mounted in the block 42 remain motion- 10 less and I have found that springs mounted in this way are not subject to the fatigue experienced by leads of other types which have been tested in this connection and that they prove durable and successful in use. 15 The springs are, as stated, preferably under a substantial compression so that no screws are necessary to hold them in and overstrain and break them at the point of attachment, their length is not great as compared with their diameter, and they are 20 stiff enough so that they do not bend appreciably under their own weight, and they have no tendency to vibrate or slap around because of their own inertia. 25 Having described my invention, what I claim as new and desire to secure by Letters Patent of the United States is:—
1. In a machine of the class described, a vibrating tool holder, a tool on said holder, an electric heating unit on the holder in convenient heat conducting relation to said tool and a lead for said unit comprising a spiral spring of substantially straight axis extending between said moving holder and the fixed frame of the machine. 30
2. In a machine of the class described, a moving tool, an oscillating tool holder, a tool on said holder, an electric unit on the holder in convenient heat conducting relation to said tool, and a conducting lead for said unit comprising a spiral spring extend- 35

ing between said oscillating holder and an adjacent part of the frame of the machine, the length of said spring not being great as compared with its diameter. 45

3. In a machine of the class described, an oscillating tool holder, a tool on said holder, an electric unit on the holder in convenient heat conducting relation to said tool upon said holder, a portion of said holder extending into close juxtaposition with the fixed frame of the machine, and a spiral spring under compression having a substantially straight axis with one end mounted on the frame and the other mounted upon the holder at these points respectively, for conducting electric energy to the unit. 50

4. In a machine of the class described, an oscillating tool holder, a tool on said holder, an electric unit on the holder in convenient heat conducting relation to said tool on said holder, a block having a socket mounted on the frame of the machine, a similar block having a similar and registering socket mounted upon the oscillating holder opposite the first named block, and a spiral spring under compression mounted with its ends in said sockets for conducting electric energy to the oscillating unit and leads passing from the ends of said spring to the unit and to a suitable source of energy, respectively. 65

5. In a machine of the class described, an oscillating tool holder, an electric unit on the holder for heating the tools on the holder, and a spiral spring lead for the unit extending from the fixed frame of the machine to the holder, having its axis straight and parallel to the axis of oscillation of the tool holder. 70

In testimony whereof I have signed my name to this specification. 80

FRANK E. BOOTHROYD.
